(74) Attorney, Agent, or Firm — Fattibene and Fattibene
LL; Paul A. Fattibene(57) **CLAIM**

The ornamental design for a torch, as shown and described.

DESCRIPTION

FIG. 1 is a front perspective view of a first embodiment of a torch showing the new design;

FIG. 2 is a right side elevation view thereof;

FIG. 3 is a left side elevation view thereof;

FIG. 4 is a top plan view thereof;

FIG. 5 is a bottom plan view thereof;

FIG. 6 is a rear elevation view thereof; and,

FIG. 7 is a front elevation view thereof.

The broken lines in the drawings depict unclaimed environmental subject matter.
